UNITED STATES PATENT OFFICE.

ROSS S. SUTTON, OF ST. LOUIS, MISSOURI, ASSIGNOR OF ONE-HALF TO
JOSEPH R. MILLER, OF ST. LOUIS, MISSOURI.

ADVERTISING DEVICE.

No. 839,334.

Specification of Letters Patent.

Patented Dec. 25, 1906.

Application filed April 1, 1905. Serial No. 253,263.

To all whom it may concern:

Be it known that I, Ross S. SUTTON, a citizen of the United States, residing at St. Louis, Missouri, have invented a new and useful Advertising Device, of which the following is a specification.

This invention relates to advertising devices; and the general object thereof is to provide a simple and effective apparatus of simple construction and capable of economical operation to vary or alter the appearance or character of the display in order more surely to attract attention, and thereby enhance the utility and value of the apparatus.

More specifically, the object of this invention is to provide a device of the class mentioned comprising a movable sign-carrying plate or sheet having words, letters, or other characters for display and an opaque front or shield having open or transparent spaces to reveal portions of the display characters when they are brought directly behind the said spaces. Mechanism is provided to impart and maintain intermittent movements to the part carrying the display characters, as required to bring different characters in the line of vision behind the open or transparent spaces in the opaque shield.

Referring to the drawings, forming part of this specification, Figure 1 is a front elevation of a device embodying my invention. Fig. 2 is a sectional view thereof, the opaque shield being removed to disclose the part carrying the characters and a portion of the operating mechanism and showing the manner of operating the device by use of a motor. Fig. 3 is a vertical sectional view taken approximately on the line 3-3 in Fig. 2 looking leftward. Fig. 4 is a view showing the construction and arrangement of the mechanism employed to impart intermittent movements to the part carrying the display characters, omitting the motor to avoid confusion. Fig. 5 is a side view of the mechanism shown in Fig. 4. Fig. 6 is a vertical sectional view taken along the line 6-6 in Fig. 5. Fig. 7 is a sectional view taken along the lines 7-7 in Figs. 4 and 6 looking leftward, as indicated by the arrows. Fig. 8 is a sectional view on the lines 8-8 in Figs. 4 and 6 looking toward the right, as the arrows indicate.

The case 10 contains the entire mechanism and is provided with an opaque front 11, having a series of open or transparent spaces

12, arranged or disposed in any preferred relation. The said front 11 may be of stained or painted glass or any other desired material, it only being necessary that there be transparent or open spaces to reveal the display characters when properly positioned. 55 A frame 13 is suspended within the case 10 and is arranged to swing longitudinally, as may be understood by reference to Fig. 2. A holding-frame 14 is pivoted to the lower part of the suspended frame 13 and is intended 60 to receive and retain the sign-carrying part 15. On the part 15 are arranged a plurality of signs, characters, or words, arranged so that during oscillation of the frame 13 they will be brought adjacent to the open or transparent 65 spaces 12, thereby forming words or other devices which it is desired to display. For instance, it can be seen by reference to Fig. 1 that there are two distinct classes of signs to be displayed and that only one at a time is 70 visible. In the drawings the visible words are "Cigars, tobacco, etc.,," and it can be seen that by swinging the frame 13 toward the right another sign comprising the words "Woolen and linen clothing" will be 75 revealed. It will be readily understood that I may change the signs or displays at will and that the form or arrangement on the part 15 is immaterial.

As before indicated, the display-carrying 85 part 15 and the frame 13 are intended to be oscillated as required to bring the display characters successively before the open or transparent places 12. To cause such oscillation, I provide a motor, which may be of 90 any suitable type and which communicates with the frame 13 by a link. An intermediate escapement operates to cause the swinging movement to become intermittent, so that the various signs or characters for display will be stopped momentarily before the open or transparent spaces 12. 95

16 indicates the motor, which may be a spring-motor or electric or any other preferred type, said motor preferably being supported near one end of the case for convenience. The construction or arrangement of this motor is immaterial. It is evident that any of the available types may be used, for which reason I have omitted illustration 100 thereof in most of the views of the drawings. The conventional illustration of a motor in Figs. 2 and 3 will be sufficient to enable those 105

skilled in the art to which the invention pertains to comprehend the manner of connection. The motor is arranged to drive a shaft 17 through the medium of a train of 5 gears and a yielding connection between one of said gears, as 18, and the shaft. The gear or pinion 18 is rigid with a sleeve 19 on the shaft 17, and a spring 20 encircles the said sleeve, one end of said spring being connected 10 to a pin or projection 21 on the pinion and the other end of said spring being connected to a disk or arm 22, rigid with the said shaft. 15 From the foregoing it will be apparent that the motor will impart motion to the shaft 17 through the medium of the connection afforded by the spring 20 and the disk or arm 22. A disk 23 is attached to the end of the shaft 17, and a link 24 is pivoted thereto outside the center, said link being also 20 connected to the frame 13, so that rotation of the shaft 17 causes the oscillation or swinging of the frame 13 and the part 15 as required to bring the various signs or displays successively before the open or transparent 25 spaces 12.

In addition to the mechanism just described it is necessary or desirable to provide means to break the continuity of the movement of the displays, so that they may remain momentarily in view. This is accomplished by an escapement device which stops the rotation of the shaft 17 for short periods while the motor continues to operate, the power being stored up in the spring 20. A 30 collar-bearing 25 for the shaft 17 extends outwardly toward the disk 23. A bar 26, having a central hole to receive the bearing, is pivoted on the bearing, and two arms 27 project from said bar toward the gear or pinion 35 18. An eccentric disk or cam 28 is rigid with the gear or pinion 18, and the arms 27 project over the periphery of said cam, as clearly shown in Figs. 4 and 6. The rotation of the cam alternately raises and lowers the arms 40 27, and thereby rocks the bar 26. A lug or projection 29 is rigid with the inner face of the disk 23 and is of sufficient length to engage the outermost end of the bar 26, as shown in Fig. 4. The parts are arranged so 45 that when one sign or group of display characters are in front of the spaces 12 the lug 29 will strike one end of the bar 26, and thereby stop the disk 23 and also the frame 13, and so hold the sign or characters in plain sight for a 50 short time. In the meantime the motor continues in operation and stores up power in the spring 20. The larger part of the cam soon passes from one arm 27 to the other, and thereby rocks the bar 26, releasing the disk 55

23. The spring 20 instantly turns the shaft 17 until the lug 29 strikes the other end of the bar 26, the arrangement being such that another sign or group of display characters is then in view. This operation is continuous, and no adjustment or other disposition of the 60 parts or mechanism will be necessary. It may be noted, however, by referring to Fig. 5 that I provide a series of places or points of attachment 30 on the disk 23 for the link 24, so that the scope of movement of the frame 70 13 may be varied.

To those skilled in this class of devices many variations will readily suggest themselves which may be embodied in devices of this kind without in the least departing from 75 the nature and principle of my invention as set forth in the appended claims.

Having thus described my invention, what I claim as new, and desire to secure by Letters Patent, is—

1. An advertising device comprising an opaque shield having transparent spaces, a swinging frame suspended behind the said shield, a holding-frame pivoted to the lower part of the swinging frame, means for moving the swinging frame and thereby the holding-frame to different positions, and means for holding said frames for predetermined periods in such positions. 80

2. An advertising apparatus comprising an opaque shield having transparent spaces, a swinging frame suspended behind said shield, a shaft, a link connection between the shaft and the swinging frame, a motor, a gear loose on the shaft, driven by said motor, spring 85 connection between the gear and the shaft, and an escapement device controlling the movement of the link connection between the shaft and swinging frame, substantially as described. 90

3. An advertising apparatus comprising an opaque shield having transparent spaces, a swinging frame carrying displays behind said shield, a motor, a shaft, a gear driven by said motor loose on the shaft, a spring connecting 95 the gear to the shaft, a link connecting the shaft to the swinging frame, an escapement, and means for causing the escapement to hold the link against movement at equidistant periods during rotation of the shaft, substantially as described. 100

In testimony whereof I have signed my name to this specification in the presence of two subscribing witnesses.

ROSS S. SUTTON.
